(57) **CLAIM**

The ornamental design for a storage container lid, as shown and described.

DESCRIPTION

FIG. 1 is a side perspective view showing my new design for a storage container lid;

FIG. 2 is a left side elevational view of the storage container lid as shown in FIG. 1;

FIG. 3 is a right side elevational view of the storage container lid as shown in FIG. 1;

FIG. 4 is a rear elevational view of the storage container lid as shown in FIG. 1;

FIG. 5 is a front elevational view of the storage container lid as shown in FIG. 1;

FIG. 6 is a top plan view of the storage container lid;

FIG. 7 is a bottom plan view of the storage container lid; and,

FIG. 8 is a side perspective view of the storage container lid. The broken line showing a cupholder tray is included for the purpose of illustration only and forms no part of the claimed design.

1 Claim, 5 Drawing Sheets
